John E. Schank
John Howard Nelson, n.s. Atty.

UNITED STATES PATENT OFFICE.

JOHN E. SCHANK, OF CHICAGO, ILLINOIS.

GOLF BAG.

Application filed August 11, 1921. Serial No. 491,835.

To all whom it may concern:

Be it known that I, JOHN E. SCHANK, a citizen of the United States, and a resident of Chicago, in the county of Cook and State of Illinois, have invented certain new and useful Improvements in Golf Bags, of which the following is a full, clear, and exact specification.

My invention is concerned with golf bags, and is particularly concerned with a novel means for adjusting the position of the handle relative to the top of the bag so as to make it more convenient for users of different statures.

It is further concerned with a novel means for securing, preferably adjustably, the lower end or both ends of the shoulder strap to the bag.

It is finally concerned with novel constructions of the bottom and top of the bag, whereby I can produce cheaply a durable structure having the desired rigidity at both ends and throughout its length.

To illustrate my invention, I annex hereunto two sheets of drawings in which the same reference characters are used to designate identical parts in all the figures, of which—

Fig. 1 is a side elevation of a golf bag having my invention applied thereto;

Fig. 2 is a horizontal section on an enlarged scale on the line 2—2 of Fig. 1;

Fig. 3 is a perspective view of the locking mechanism;

Fig. 4 is a view in section on the line 4—4 of Fig. 3, but on a larger scale;

Fig. 5 is a side elevation of a golf bag with my adjustable handle and novel shoulder strap connection, and novel top and bottom applied thereto;

Fig. 6 is a longitudinal section, on an enlarged scale on the line 6—6 of Fig. 5;

Fig. 7 is a horizontal section on an enlarged scale on the line 7—7;

Fig. 8 is a vertical section on an enlarged scale on the line 8—8 of Fig. 5; and

Fig. 9 is a vertical section on an enlarged scale on the line 9—9 of Fig. 7.

In carrying out the pocket portion of my invention, I may apply it to any desired form of a golf bag 10, which bags are usually provided with the carrying strap 11 and the handle 12, and a pocket 13 secured on the outside of the bag and provided with the flap 14 having the strap 15 co-operat-

ing with the buckle 16 on the body of the pocket. All of the construction so far described is ordinary and well known and, per se, forms no part of my pocket invention.

In carrying out my invention in its preferred form I secure upon the body 10 by the rivets 17 and 18, or some similar fastening, which pass through said body and the adjacent portion of the flap 14, a metallic bar 19 which is of sufficient rigidity so that it cannot be readily bent or otherwise affected, and in the center of this bar I mount a locking eye 20, which preferably has its stem end 21 reduced and secured to rotate in the rearwardly flaring aperture 22 formed in the center of the bar 19. Along the upper edge of the top of the pocket 13, as by the rivets 23 I secure a bar 24, preferably somewhat shorter than the bar 19, but in the same vertical plane, and having formed therein the elongated aperture 25 through which the eye 20 can be passed when it is desired to close securely the pocket. After the eye is passed through the aperture 25, as seen in Fig. 4, the eye is turned to the position shown in Fig. 3, in which the bar 24 is held rigidly so close to the bar 19 that it is impossible for any balls accidentally to work out of the pocket. The pocket will ordinarily be held closed simply by the mechanism described, while a game is being played, but after the game is finished, and before the bag is turned over to the caddy to take to the shop, the player will snap the padlock 26 in place, it being understood that he will be provided with a padlock having the hasp 27 adapted to pass through the eye 20 and be locked when it is pressed home in the customary manner.

In order to improve the appearance of the pocket, the flap 14 is preferably bound by a strip 28, seen in section in Fig. 4, and the top of the body of the pocket is preferably bound by the strip 29 seen in section in Fig. 4, the parts of which have their thickness exaggerated for convenience in illustration.

Referring to my novel adjustable handle construction shown in Figs. 5 and 6, it will be seen that I have secured to the body 10 of the bag above the pocket 13 a rigid strip 30, preferably formed of elastic sheet metal, and covered by the strip of leather or fabric 31 sewed at its edges to the body 10. This strip

30 is provided with a plurality of spring clips 32, which may be stamped out of the body of the strip, and are in the form of tongues, having the outwardly inclined tip 5 33 and the re-entrant portion 34 so that there is a wider portion 35 at the top which is adapted to receive and hold yieldingly the links 36 which are pivoted in the top and bottom of the handle 12. With this construction, it will be obvious that the links 36 10 can be withdrawn from the particular clips 32 with which they may be engaged and replaced in other clips so as to vary the position of the handle on the bag. 15 Where this strip 30 is employed, I preferably secure thereto the ends of the shoulder strap 11, preferably by providing the ends of the strap 11 with the loops 37 which carries the links 38 which in turn are adapted 20 to be secured to any desired ones of the clips 32 in the same manner as the links 36. With this construction it will be obvious that the shoulder strap can be quickly detached from the bag, if desired, and secured thereto at 25 different points to vary the position of the shoulder strap.

In carrying out my invention in its preferred form, I secure on the top thereof the rigid annulus 39, which is preferably made 30 of a strip of sheet metal, and is preferably provided with a curved flange 40 at its upper end overhanging the edges of the top of the bag as well as the customary leather stiffening strip 41 which is sewed at its lower edge 35 to the body 10. To secure the desired rigidity of the body of the bag and prevent its collapsing, I preferably employ two or more stiffening rods 42 which are provided with the eyes 43 at their upper ends and the corresponding eyes 44 at their lower ends. 40 These rods are protected and held in place by the covering strips 45, preferably formed of leather, and extending the length of the bag to the eyes 43 and 44, and sewed at their edges to the body 10. The annulus 39 preferably has the flange 40 curved sufficiently so that its edge 46 grips and clamps the body 10 and the stiffening strip 41, between it and the body of the annulus, as clearly seen 50 in Fig. 9. As I wish to employ different numbers of stiffening rods 42 for different sized bags, instead of employing the rivets 47, which, as seen in Fig. 9 pass through the body 10, eye 43, and strip 41, to hold the annulus 39 in place, I employ other rivets 48 55 for this purpose, these rivets passing only through the annulus 39, body 10 and strip 41.

In the preferred form of my invention, I 60 secure on the bottom the preferably metallic stiff cap 49, which has the upwardly extending flange 50 at its edge, and through which flange 50 pass the rivets 51 through the lower end of the stiffening strip 42 and the body 10. To deaden the noise which the

ends of the shaft would make when they are dropped in the bag, I secure upon the inside of the metallic bottom cap 49 the pad 53 of felt, or any other similar material.

By the construction shown, in which I 70 have the metallic bottom and the metallic annular flange at the top, with the connecting stiffening rods 42 preferably riveted thereto as well as to the reinforcing strips 41 and 52, I produce a rigid, yet comparatively 75 light and cheaply constructed bag, which will stand more abuse than those heretofore constructed with which I am acquainted.

While I have herein shown and described a novel locked pocket for a golf bag, I do not 80 herein claim the same, as it is covered in my application No. 595,044, filed October 17, 1922, which I hope to have issued simultaneously herewith.

While I have herein shown and described, 85 and claimed specifically, one adjusting means for the handle and strap, said means are claimed generically in my aforesaid application No. 595,044.

While I have shown and described my invention as embodied in the form which I at present consider best adapted to carry out its purposes, it will be understood that it is capable of modifications and that I do not desire to be limited in the interpretation of 90 the following claims, except as may be necessitated by the state of the prior art.

What I claim as new and desire to secure by Letters Patent of the United States is:

1. In a golf bag, the combination with a body, of a rigid bar secured to the upper part of the body, a handle, and means for detachably securing said handle to the bar in any desired one of several different positions. 100

2. In a golf bag, the combination with a body, of a rigid bar secured to the body having a plurality of downwardly opening spring clips extending downwardly therefrom, and a handle having links pivoted in the ends thereof and adapted to be caught in the clips. 110

3. In a golf bag, the combination with a body, of a rigid bar having a plurality of downwardly opening spring clips extending outwardly therefrom struck up from the body thereof, a cover strip for the bar secured at its edges to the body of the bag and having transverse slots therein through which the clips extend, and a handle having links pivoted in the ends thereof and adapted to be caught in the clips. 115

4. In a golf bag, the combination with a body, of a rigid strip secured thereto extending along the upper half of the bag and having downwardly opening spring clips extending outwardly therefrom, and a shoulder strap secured at one end to the bag and having a link at its other end adapted to be caught in any desired one of said clips. 125 130

5. In a golf bag, the combination with a flexible body, of an annular bendable stiffening strip secured around the outside of the open top of the body, a rigid metallic annulus inside of the top of the body and having an exposed outwardly extending flange overhanging the stiffening strip, and rivets for securing the body, strip and annulus together.
- 10 6. In a golf bag, the combination with a flexible body, of an annular bendable stiffening strip secured around the outside of the open top of the body, a rigid metallic annulus inside of the top of the body and having an exposed outwardly extending flange overhanging the stiffening strip and clamping the top thereof to the body, and rivets for securing the body, strip and annulus together.
- 15 7. In a golf bag, the combination with a flexible body, of an annular bendable stiffening strip secured around the outside of the top of the body, a rigid metallic annulus inside of the top of the body and having an exposed outwardly extending flange overhanging the stiffening strip, rivets for securing the body, strip and annulus together, stiffening rods provided with eyes at their upper ends, covering strips secured at their edges to the body and holding the rods in place, and other rivets extending through the strips, eyes and body.
- 20 8. In a golf bag, the combination with a flexible body, of an annular bendable stiffening strip surrounding the bottom of the body, metallic stiffening rods having eyes at their lower ends, cover strips for the rods secured at their edges to the outside of the body, a cup-shaped metallic bottom piece associated with the lower end of the body, the stiffening strip and cover strips and stiffening rods, and rivets extending through the flange of the bottom piece, eyes, stiffening strip and body to secure them together.
- 25 9. In a golf bag, the combination with a flexible body, of bendable annular stiffening strips secured around the outside of the top and of the bottom of the body, a plurality of metallic stiffening rods having eyes at their top and bottom interposed between the body and the stiffening strips, cover strips for the rods secured at their edges to the outside of the body, a rigid metallic annulus inside of the top of the body and having an exposed outwardly extending flange overhanging the stiffening strip, a cup-shaped metallic bottom piece associated with the lower end of the body, the stiffening strip, the stiffening rods and their cover strips, and rivets for securing the aforesaid parts together, substantially as and for the purpose described.
- 30

In witness whereof, I have hereunto set my hand and affixed my seal, this 8th day of August, A. D., 1921.

JOHN E. SCHANK. [L. S.]
Witness:
JOHN HOWARD McELROY.
